EMBOSSED TEXTILE FABRIC

Abraham Shurr, New York, N. Y., assignor to Shurr
Fabrics Inc., New York, N. Y., a corporation of New York

Application July 27, 1955, Serial No. 37,144

Term of patent 3½ years

(Cl. D92—1)

The figure is a plan view of an embossed textile fabric, showing my new design.

A unit of the design is enclosed within the dot and dash lines on the drawing.

I claim:

The ornamental design for an embossed textile fabric, substantially as shown and described.
